US00D610257S

(12) **United States Design Patent**
Horton

(10) **Patent No.:** **US D610,257 S**
(45) **Date of Patent:** **** Feb. 16, 2010**

(54) **SURGICAL DRILL GUIDE**

(76) Inventor: **Kenneth L. Horton**, 327 Shades Crest Rd., Birmingham, AL (US) 35226

(**) Term: **14 Years**

(21) Appl. No.: **29/329,539**

(22) Filed: **Dec. 17, 2008**

(51) **LOC (9) Cl.** **24-02**

(52) **U.S. Cl.** **D24/140**

(58) **Field of Classification Search** D24/133, D24/135, 112, 146, 140; D15/132, 138-139; 606/87-89, 96-98, 102, 167, 170

See application file for complete search history.

(57) **CLAIM**

I claim the ornamental design for a surgical drill guide, as shown and described.

DESCRIPTION

FIG. 1 is a top perspective view of a surgical drill guide showing my new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
